(57) **CLAIM**

The ornamental design for a mobile phone, as shown and described.

DESCRIPTION

FIG. 1 is a front perspective view of the mobile phone showing our new design in a closed state;

FIG. 2 is a front view thereof;

FIG. 3 is a rear view thereof;

FIG. 4 is a left side view thereof where the right side view is a mirror image;

FIG. 5 is a top plan view thereof where the bottom plan view is a mirror image;

FIG. 6 is a front perspective view of the mobile phone of FIG. 1, shown in an extended state;

FIG. 7 is a front view of FIG. 6;

FIG. 8 is a rear view of FIG. 6;

FIG. 9 is a left side view of FIG. 6 where the right side view is a mirror image;

FIG. 10 is a top plan view of FIG. 6 where the bottom plan view is a mirror image; and,

FIG. 11 is a rear perspective view of FIG. 6.

1 Claim, 11 Drawing Sheets
